(57) **CLAIM**

The ornamental design for a grill cleaning tool, as shown and described.

DESCRIPTION

FIG. 1 is a front perspective view of the grill cleaning tool of the present invention.

FIG. 2 is a top view of the grill cleaning tool of FIG. 1, with the bottom view being identical thereto.

FIG. 3 is a right side view of the grill cleaning tool of FIG. 1, with the left side view being a mirror image thereof.

FIG. 4 is a front view of the grill cleaning tool of FIG. 1; and, FIG. 5 is a rear view of the grill cleaning tool of FIG. 1.

The broken lines in the figures depict a boundary between claimed and unclaimed areas that forms no part of the claimed design.
